ACCESSORY FOR FLOWN KITES

Charles H. Shoemaker, Glendale, Calif.

Application September 15, 1948, Serial No. 49,392

10 Claims. (Cl. 244—155)

1

This invention relates to kite accessories and particularly to an improved device which is readily attached to a kite string and which may be employed to slide upward along the kite string under the influence of wind currents and to carry up objects such as parachutes, messages, gliders, and the like and to release the load thus carried at a predetermined point along the kite string after which the device will slide down the string to the holder.

An object of the invention is to provide a device of the above character having a flexible resilient wing structure with consequent simplification of construction over devices heretofore used and an incident reduction in cost.

Another object of the invention is to provide a kite string traversing device having a flexible and resilient wing structure which upon release will revert into such form that the resistance to wind is reduced whereby the device will be returned down the kite string by gravity.

A further object of the invention is to provide a kite string traversing device adapted to carry and release objects which is so constructed and arranged that the object carried is first released and then the wing structure is released and permitted to assume its normal form for the return trip.

Still another object of the invention is to provide a device of the above character in which the object and wing release means is so designed as to effect a positive release of the object carried and of the wing structure.

A still further object of the invention is to provide a device of the above character having a body member which serves as a guide and housing for the release operating means.

A still further object of the invention is to provide a device of the above character having a wing structure which is flexible and which will yield to excessive wind pressure with consequent reduction in effective area and reduction of the chance of damage to the device.

Still another object of the invention is to provide a kite string traversing device having the above desirable objects which is composed of few parts, is of simple design, is easy and economical to manufacture and which is reliable in operation.

With the foregoing objects in view, together with such other objects and advantages as may hereinafter appear, the invention resides in the parts and in the construction, combination and arrangement of parts described in the following

2

specification; reference being had to the accompanying drawings, in which:

Fig. 1 is a perspective view of the device attached to a kite string with the wing structure locked in its spread or open position and with a parachute attached for subsequent release,

Fig. 2 is a fragmentary, larger scale, side elevation of the front and rear ends of the device showing the relation of the component parts at the instant of release of the load and of the retaining means for the wing structure.

Fig. 3 is a fragmentary bottom plan view of the front end and wing structure of the device,

Fig. 4 is a perspective view of the fixed element of the locking and releasing means for the load and wing spreading means,

Fig. 5 is a fragmentary transverse sectional view of one of the wings, showing a means for resiliently reinforcing the wings, taken on the line 5—5 of Fig. 3, and

Fig. 6 is an enlarged, fragmentary, sectional view taken on the line 6—6 of Fig. 3.

The illustrated form of the invention comprises a body member 1 formed of a rectangular piece of light wood or other suitable material, such as plastic, and having a groove 2 extending from end to end along the lower face thereof. The forward upper end of the body member carries the shank 3 of an upstanding pigtail eyelet 4 formed from plastic or other smooth surfaced material into which eyelet the kite string S may be inserted through the opening between the end of the eyelet and the other side of the eyelet loop, and mounted in the forward end of the groove 2 is a tubular guide 5 for the release rod 6 slidably mounted in the groove 2. A strip of adhesive tape 7 wound about the forward end of the body member over the eyelet shank 3 and the guide 6 serves to hold both firmly secured in place on the body member 1. If desired, the wire 6 can be further retained in the groove 2 by a wire or other wrapping 7' located midway between the front end of the device and the point of attachment of the wing structure.

Mounted on the upper face of the rear end of the body member 1 is the shank 8 of a second pigtail eyelet 9, also preferably formed of plastic, disposed in longitudinal alignment with the eyelet 3 and adapted to be similarly engaged by the kite string S, and mounted on the under face of the rear end of the body member is the stationary portion of the load and wing release means comprising a pair of shallow, inverted U-shaped strips 10 and 11, nested one within the other, the

forward arms 10' and 11' of which depend, angularly forward and the rear depending of arms 10" and 11" of which are disposed at right angles to the plane of the under face of the body member 1. A wrapping of adhesive tape 12 serves to secure both the eyelet shank 9 and the strips 10 and 11 firmly to the body member 1 with the arms 10' and 11' spaced apart to form a clearance 13 into which the attached part of the load to be carried may be inserted. The back of the member 10 also covers the rear end of the groove 2 and thus cooperates therewith to form a rear guide for the wire 6. While here shown as separate pieces, the strip elements may be made as a unitary plastic molding and it or they may be otherwise attached to the body member without departure from the invention.

The wing structure comprises a pair of identical wings and a description of one will suffice for both. The wing 14 is formed from heavy paper or the like which, preferably, is treated to render it waterproof. The shape of the wing is optional; the form illustrated being to some extent a simulation of the outspread wing of a bird. The base 15 of the wing is straight and is secured by gluing or other appropriate means to a wooden base member 16. The wing is reinforced and given resilience by a resilient rib element comprising a normally substantially straight strip of clock spring 17 disposed on the front face of the wing and extending from the base member 16 lengthwise of the wing to a point adjacent the wing tip 18. A strip of adhesive tape 19 overlying the clock spring and extending on both sides thereof secures the clock spring to the wing surface. Other means of securing the spring to the wing will suggest themselves to those skilled in the art. For example, the spring may be interlaced in a series of spaced slots in the wing.

The wing base members 16, 16 are connected together in spaced relation by a spacing block 20 at the lower ends of the base members and are attached to the opposite sides of the body member 1 at a point about one-third of the distance from the rear to the front end of the body member with the spring elements 17, 17 extending parallel to and just below the lower face of the body member. A brad 21 extends through the members 16, 16 and the spacing block 20 and a second brad 22 unites the members 16, 16 and the body member 1. The ends of the spring elements extend a short distance beyond the members 17, 17 and are engaged by a block 23 inserted between the wing bases and secured against the under face of the body member 1 by a wrapping 24 of adhesive tape or the like which serves to secure the ends of the springs 17, 17 against the sides of the block 23 and the block being seated against the underside of the body member 1 operates to retain the wire 6 within the groove 2.

Attached to the underside of each wing 14, spaced a short distance from the wing base is one end of a pair of cords, 25, 25, the opposite ends of which are secured to loops or eyes, 26, 26, at opposite ends of a link which link has a mid-portion 27 adapted to engage the rear face of the depending arm 11' and the cords 25, 25 are of such length that when the link 26 is thus engaged the wings 14, 14 will be pulled down and will extend substantially at right angles to the body member 1 against the tendency of the spring elements 17, 17 to return the wings to a closed position substantially parallel to the body member 1 (as shown in dotted lines in Figs. 1 and 3). The wire 6 at its front end is bent upwardly and

terminates in a large pigtail eyelet portion 28, adapted to pass around but not engage the kite string S and the rear end of the wire 6 beyond the end of the body member is turned downwardly at 29 and terminates in a forwardly projecting portion 30, which passes through aligned holes 31 in the depending arms 10", 11", 11' and 10'. The wire 6 is of such length that when it is moved rearwardly until the shank of the eyelet 28 engages the front end of the body member 1, the forwardly projecting end portion 30 will be in the holes 31 in the arms 10" and 11" only, whereby these holes serve as guides to prevent the wire from turning and when the wire is moved forward until the portion 29 engages the rear face of the member 10" the portion 30 will extend through and beyond the holes 31 in the arms 11' and 10'.

In use, a kite K is first flown after having a cork C or other stop means attached to the kite string S some distance (usually short) below the kite. Then the device constituting the present invention is mounted on the kite string by working the kite string into the eyelets 3, 9 and 28. When so mounted, the device will slide on the eyelets 4 and 9 but the eyelet 28 will not contact the string. Then the wire 6 is moved rearwardly as far as it will go and the link 27 is placed back of the arm 11' and the wire moved forward so that the end thereof will pass through the hole 31 in the arm 11' below the link 27, thus locking the wings in a balanced spread position, each 90°. Next the article to be carried and released, such as a parachute P, having an attaching loop L is engaged over the end of the wire in the clearance space 13 and the wire is moved all the way forward with the end thereof passing through the hole 31 in the arm 10'. Upon release, the wind will carry the device up the kite string until the eyelet 28 engages the stop member C at which time the wind pressure will move the body member 1 up along the kite string and the wire with resultant movement of the arms 10" and 11' upwardly off the end 30 of the wire. Alternatively, the Y or bridle attaching the kite to the kite string may be employed as the stop. As soon as the wire clears the space 13, the parachute or other load will be dropped and as soon as the wire clears the member 11', the tension on the springs 17, 17 will pull the link 27 off the forwardly sloping rear face of the member 11' with resultant release of the tension whereupon, the springs 17, 17 will cause the wings 14, 14 to assume a position substantially parallel to the body member 1 and the device then will slide down the string S to the holder after which it can be reloaded and reset for another trip.

The flexible wing construction possesses several advantages over the rigid hinged wings that characterize prior art devices for the same purpose. First, being resilient, the wings fold quickly and automatically upon release. Second, no rigid wing frame and hinge is required. Third, in the presence of excessive wind, the tips of the wings will yield forwardly as indicated in dotted lines in Fig. 3 and reduce the area exposed to the wind. Fourth, this capacity of the wings to yield to excessive loads acts as a shock absorber at the instant of contact with the stop means on the kite string and thus protects the device from damage.

The novel locking and release means also possesses advantages over the prior art structures. First, the successive release of the load and then the wing structure insures that the load will be

stripped of the locking portion 38 of the wire 6 before the wings are released. Second, the forward sloping of the arms 10 and 11 insures that the load and the link portion 21 will slide free when unlocked. Third, the folding movement of the wings, pulling the locking link across the space 13 in which the load is secured insures that should the load tend to drag in that space, the traverse of the link across this space will positively effect dislodgment. It is also to be noted that the eyelet 28 is of such size that it will not engage the kite string and thus it can not accidentally effect the premature release of the load.

Further, by employing a groove in the body member to guide the load and wing locking and releasing wire, a much lighter wire or rod can be employed with consequent reduction in weight and without significant loss of strength of the body member.

While the foregoing specification has described a specific mode of execution of the invention, I do not intend thereby to limit myself to the exact form there disclosed, and the invention includes all such modifications in the parts and the materials from which they are made and all such modifications in the combination and arrangement of such parts as shall come within the purview of the appended claims.

I claim:

1. A load carrying and releasing accessory for use with flown kites comprising a body member having spaced eyelets adapted to be engaged with a kite string, a pair of resilient wings each having one end thereof immovably attached to said body member, a single means for releasably securing said wings in spread position and securing an article to be carried by said accessory to said body member, and means operable upon contact with a stop on the kite string to release the article.

2. A load carrying and releasing accessory for use with flown kites comprising a body member having means for being mounted in free sliding engagement on a kite string, a pair of flexible and resilient wings each having one end thereof rigidly attached to said body member and normally disposed in planes substantially parallel to the kite string, means for releasably locking said wings in spread position and means operable upon contact with a stop on the kite string to release the wings with incident return of the wings to their normal position by reason of their resilience.

3. A load carrying and releasing accessory for use with flown kites comprising a body member carrying eyelets adapted to permit attachment of the body member to a kite string, a flexible and resilient wing structure rigidly attached to said body member and normally disposed in parallel relation thereto, devices carried by said body member constructed and arranged to separately and releasably secure an article to be carried to said body member and to lock said wing structure in spread position and including means operable upon contact with a stop on the kite string to first effect the release of the article and then to release said wing structure with incident return thereof to its normal position.

4. A load carrying and releasing accessory for use with flown kites comprising a body member carrying eyelets adapted to permit attachment of the body member to a kite string, a flexible and resilient wing structure rigidly attached to said body member and normally disposed in parallel relation thereto, devices carried by said

body member constructed and arranged to separately and releasably secure an article to be carried to said body member and to lock said wing structure in spread position and including means operable upon contact with a stop on the kite string to first effect the release of the article and then to release said wing structure with incident return thereof to its normal position; the return of said wing structure to its normal position being further operative to insure the clearing of the article from its securing means.

5. A load carrying and releasing accessory for use with flown kites comprising an elongated, rigid body member having a longitudinal groove on one face thereof, aligned kite string receiving eyelets affixed to each end of the body member, a pair of resilient wing elements affixed to opposite sides of said body member; each of said wing elements including a resilient rib element normally tending to maintain the wing element with which it is associated in a position substantially parallel to said body member and devices including a rod mounted for reciprocation in said groove for releasably locking said wing elements in open or spread position and for releasably securing an article to be carried and released at a predetermined point on the kite string.

6. A load carrying and releasing accessory for use with flown kites comprising an elongated, rigid body member having a longitudinal groove on one face thereof, aligned kite string receiving eyelets affixed to each end of the body member, a pair of flexible wing elements affixed to opposite sides of said body member; each of said wing elements including a resilient rib element normally tending to maintain the wing element with which it is associated in a position substantially parallel to said body member and devices including a rod mounted for reciprocation in said groove for releasably locking said wing elements in open or spread position and for releasably securing an article to be carried and released at a predetermined point on the kite string; said rod at its forward end having an eyelet into which the kite string may be inserted and at its rear end terminating in a locking portion extending downwardly and thence forwardly and movable into and out of aligned openings in a series of arms depending from said body member.

7. A load carrying and releasing accessory for use with flown kites comprising an elongated, rigid body member having a longitudinal groove on one face thereof, aligned kite string receiving eyelets affixed to each end of the body member, a pair of flexible wing elements affixed to opposite sides of said body member; each of said wing elements including a spring normally tending to maintain the wing element with which it is associated in a position substantially parallel to said body member and devices constructed and arranged to releasably lock said wing elements in spread position and for releasably securing an article to be carried and released including a wire mounted for reciprocation in said groove and having a stop engaging portion at its forward end, a pair of arms depending vertically from the rear end of said body member, a second pair of arms spaced forwardly from said first named pair and depending angularly forwardly from said body member, aligned openings in all of said arms and a downwardly and thence forwardly projecting portion of said wire slidably engaging said holes.

8. A load carrying and releasing accessory for

use with flown kites comprising an elongated, rigid body member having a longitudinal groove on one face thereof, aligned kite string receiving eyelets affixed to each end of the body member; a pair of flexible wing elements affixed to opposite sides of said body member; each of said wing elements including a spring normally tending to maintain the wing element with which it is associated in a position substantially parallel to said body member and devices constructed and arranged to releasably lock said wing elements in spread position and for releasably securing an article to be carried and released including a wire mounted for reciprocation in said groove and having a stop engaging portion at its forward end, a pair of arms depending vertically from the rear end of said body member, a second pair of arms spaced forwardly from said first named pair and depending angularly forwardly from said body member, aligned openings in all of said arms, a downwardly and thence forwardly projecting portion of said wire slidably engaging said holes; a cord attached to the rear face of each wing element, a link element connecting the other ends of said cords; said link being adapted to be secured against the rear face of said second named pair of arms by the engagement of said wire with the holes in said arms with resultant holding of said wing elements in spread position.

9. A load carrying and releasing accessory for use with flown kites comprising a body member having spaced eyelets adapted to be engaged with a kite string, a pair of resilient wings rigidly secured to said body member, means for releasably securing an article to be carried and released to said body member, and means operable upon contact with a stop on the kite string to release the article; said article securing and releasing means comprising a pair of spaced arms depending from said body member having aligned holes adjacent the free ends thereof and an element movable into said holes to secure the ar-

8
ticle between said arms and movable out of said holes to release the article.

10. A load carrying and releasing accessory for use with flown kites comprising a body member having means for being mounted in free sliding engagement on a kite string, a pair of flexible and resilient wings rigidly secured to said body member and normally disposed in planes substantially parallel to the kite string, means for releasably locking said wings in spread position and means operable upon contact with a stop on the kite string to release the wings with incident return of the wings to their normal position by reason of their resilience; said wing locking and releasing means comprising spaced arm elements depending from said body member and having aligned holes adjacent the free ends thereof, a link element attached to the rear face of each of said wings and adapted to be inserted between 15 said arm elements and an element movable into said holes to lock said link between said arms and movable out of at least one of said holes to release said link.
